A. BEBEL

ADJUSTABLE HOOK AND EYE TAPE SECURING GUIDE

Filed Nov. 7, 1923

INVENTOR

INVENTOR
Abraham Bebel

BY *Solomon H. Polachek*
ATTORNEY

UNITED STATES PATENT OFFICE.

ABRAHAM BEBEL, OF NEW YORK, N. Y., ASSIGNOR TO THE DE LONG HOOK AND EYE COMPANY, OF PHILADELPHIA, PENNSYLVANIA, A CORPORATION OF PENNSYLVANIA.

ADJUSTABLE HOOK-AND-EYE-TAPE-SECURING GUIDE.

Application filed November 7, 1923. Serial No. 673,250.

To all whom it may concern:

Be it known that I, ABRAHAM BEBEL, citizen of Poland, residing at New York, in the county of New York and State of New York, have invented certain new and useful Improvements in Adjustable Hook-and-Eye-Tape-Securing Guides, of which the following is a specification.

This invention relates to devices which are adapted to be attached to sewing machines for facilitating the sewing of hook and eye tape upon articles of wearing apparel such as brassières, corsets, corselettes and the like, and it has for its general object to provide a device or attachment of the character indicated with means whereby it may be readily attached to and detached from the top plate or table of a sewing machine adapted for sewing such tape in place upon articles of the general character above indicated.

It is also an object of the invention to provide a device or attachment of the character indicated with means for guiding and holding tape in proper relation to the sewing mechanism of the sewing machine.

A further object of the invention is to provide a novel construction of adjustable guiding means to receive and guide tapes of varying widths and also tapes having hook or eye elements of different or varying sizes thereon.

For a full understanding of the invention and of the objects and advantages thereof reference should be had to the description thereof which follows, to the appended claims in which the invention is particularly set forth, and to the drawing in which I have illustrated one convenient form of embodiment thereof. However, it will be understood that the invention is susceptible of embodiment in other forms of construction than that shown and that changes in the details of construction may be made within the scope of the claims without departing from the principle thereof.

In the drawing:

Fig. 1 is a bottom plan view of a device or attachment embodying the invention;

Fig. 2 is a bottom plan view of the top portion of said device or attachment;

Fig. 3 is a longitudinal sectional view taken on the line 3—3 of Fig. 1;

Fig. 4 is a transverse sectional view taken on the line 4—4 of Fig. 1; and

Fig. 5 is a view in elevation of the feed device of the sewing machine for feeding the tape to the sewing mechanism.

Referring to the drawing, it will be seen that the device or attachment which embodies my invention comprises a bottom plate 10 of rectangular shape from which projects a relatively narrow extension 10' from one side or edge thereof. The said extension is provided at its outer end with lateral projections 10". In other words, the outer end of said extension is of T-shape. Bars 12 of rectangular shape in cross section are secured to the top side of the plate 10 adjacent to and parallel with the opposite edges thereof by means of screws 13. These screws engage threaded apertures 14 in the said bars 12. A plate 16 is secured to the upper or top sides of the bars 12 which plate is of the same general shape and dimensions as the plate 10 and is provided on the rear edge thereof with a shorter and wider extension 16' which extends over and covers a portion of the extension 10' previously referred to. Plates or leaves 18 are located between the top plate 16 and the bars 12. The inner edges of these plates are spaced from each other, as indicated in the drawing, and are adapted to be adjusted toward and from each other as will be more fully pointed out hereinafter. Each of these plates is provided with narrow fingers 19 which extend longitudinally rearwardly from the inner edges thereof underneath the extension 16'.

The plate 16 is secured to the bars 12 by means of screws 20 which pass through transversely extending slots 21 in the plates or leaves 18. By loosening the screws 20 the plates or leaves 18 may be adjusted toward or from each other as may be desired.

The tape, as it is fed to the sewing mechanism of the sewing machine, passes between the oppositely disposed inner edges of the plates or leaves 18 which serve to guide the tape to the said mechanism. Located between the top and bottom plates 10 and 16 within the space between the side bars 12 and spaced from the latter are two pairs of bars 24 and 25, the former constituting

an outer and the latter an inner pair. These bars extend along the opposite sides of and in parallel relation to the extension 10'. The under sides of the front end portions thereof are recessed or cut away to receive the bottom plate 10, and notches are formed upon the bottom sides of the rear ends thereof to receive the lateral projections 10^a at the rear end of the extension 10'. The bottom sides of the bars 24 and 25 are flush with the bottom face or side of the extension 10'. Both pairs of bars 24 and 25 are adapted to be laterally adjusted. The bars 24 are secured to the plate 10 by means of pairs of screws 27 which pass through transverse slots 28 in the bottom plate 10 while the bars 25 are secured to the said plate 10 by means of screws 29, certain of which extend through transverse slots 30 in the plate 10 and others through transverse slots 30' in the lateral projections 10^a. The bars 24 and 25 are provided near their rear ends with notches 32 which are of considerable length as shown. These notches are complementary to each other and form openings of rectangular shape which extend in parallel relation to the opposite sides of the rear extension 10'. The feed dogs or legs of a feed member project through these openings or apertures.

The said feed member is of the usual type employed in sewing machines for sewing tape upon brassières and other articles. It comprises a pair of separated feet or dogs 35 which are capable of adjustment toward and from each other. The base end portions of these feet or dogs are provided with offset extensions 36 which engage in dovetail grooves in the body part 37 of the structure to which they are secured by means of screws 38.

The extension 10' previously referred to is provided with an aperture 40 which extends therethrough which serves to receive a screw for fastening the device or attachment to the top plate or table of a sewing machine. It will be understood that a suitable threaded hole is provided in the said plate or table to receive the said screw.

In the employment of the device or attachment the tape, a portion of which is shown at T, is passed underneath the top plate 16 between the opposing edges of the plates or leaves 18 and is guided by said plates or leaves. Any hooks or eyes which may be secured to the tape pass between the bars 25 and are guided thereby. Hooks H are indicated in dash and dot lines upon the tape T.

The plate 16 may be provided with a slot 45 to facilitate the insertion of a tape into and through the passageway through the device at the beginning of an operation of sewing the same upon a garment or other article. The edge of an article such as a

brassière or other garment is placed upon the device or attachment and will contact with the tape immediately beyond the rear end of the extension 16'. The tape is secured to the article by a row of stitches 70 through the tape and through the said article adjacent each edge of the tape, the said stitches being formed by the usual pair of needles employed in sewing machines for attaching hook and eye tape and the like to articles of the character hereinbefore indicated.

It will be seen that by my invention I have provided an attachment for the purpose indicated of simple construction which 80 is provided with adjustable means for guiding the opposite edges of the tape and also with adjustable means for guiding the hooks or eyes or other similar articles which may be mounted upon the tape.

Having thus described my invention what I claim as new and desire to protect by Letters Patent of the United States is as follows:

1. A sewing machine attachment comprising top and bottom plates, side bars interposed between said plates and to which the latter are secured, and laterally adjustable guide bars extending between the plates between and parallel to the said side bars, and other guide elements in the form of leaves interposed between the top plate and the said side bars.

2. A sewing machine attachment comprising top and bottom plates, side bars interposed between said plates and to which the latter are secured, and laterally adjustable guide bars extending between the plates between and parallel to the said side bars, and other guide elements in the form of leaves interposed between the top plate and the said side bars, said leaves being laterally adjustable.

3. A sewing machine attachment comprising top and bottom plates, side bars interposed between said plates and to which the bottom plate is directly secured, leaves interposed between the top plate and the said bars, said leaves being provided with transverse slots, screws passing through the top plate and the said slots to bind the top plate and the leaves to the said bars, pairs of bars located between the side bars and means for adjustably connecting said pairs of bars to the said bottom plate.

4. A sewing machine attachment comprising top and bottom plates, side bars interposed between said plates and to which the bottom plate is directly secured, leaves interposed between the top plate and the said bars, said leaves being formed with transverse slots, screws passing through the top plate and the said slots to bind the top plate and the leaves to the said bars, pairs of bars located between the side bars, and means

- for independently and adjustably connecting the said pairs of bars to the bottom plate, said bottom plate having an extension, and said last named bars projecting along said 5 extension beyond the said plates and being recessed to provide slots for accommodating the work feed device of the machine.
5. A sewing machine attachment comprising top and bottom plates, spacer bars interposed between said plates and located adjacent the opposite edges thereof, said bars being connected to said plates, independently adjustable guiding means for guiding the opposite edges of a strip of tape located between the said bars and the top plate, a couple of pairs of adjustable bars located between the said plates in the space between the said spacing bars, one of the said pairs of bars constituting guiding means for guiding 10 hooks or other devices mounted upon such tape.
6. An attachment which is adapted to be mounted in co-operative relation to the sewing mechanism of a sewing machine for guiding hook and eye tape to said mechanism, the said attachment comprising a bottom plate, a top plate, spacing bars located between said plates adjacent the opposite edges thereof, means for connecting the said 15 bottom and top plates to the said spacing bars, plates adjustably mounted between the top plate and the said spacing bars, the inner edges of the said plates being spaced from each other and constituting guides for the 20 opposite edges of said tape, and laterally adjustable bars mounted between said plates and within the space between the said spacing bars, the said adjustable bars being 25 spaced from each other and constituting guides for the hooks or eyes which may be 40 mounted upon the said tape.
7. An attachment which is adapted to be mounted in co-operative relation to the sewing mechanism of a sewing machine for guiding hook and eye tape to said mechanism, comprising in combination a bottom plate which is provided with an extension which projects rearwardly from the rear edge thereof, a top plate, spacing bars interposed between said plates, means for securing said plates 45 to said spacing bars, means located between the said top plate and spacing bar, the inner edges of which are spaced from each other and constitute guides for the opposite edges of said tape, a couple of pairs of bars connected to one of the said plates and being adjustable laterally with respect thereto, the rear portions of said bars extending 50 on opposite sides of and in parallel relation to the extension from the rear edge 55 of the said bottom plate, the inner pair of said adjustable bars being spaced from each other and constituting guides for hooks or eyes upon the said tape, and the outer sides of the inner pair of bars and the inner 60 sides of the outer pair of bars being provided adjacent their rear ends with notches which are complementary to each other and which form rectangular shaped openings 65 through which feeding means of the sewing machine project to engage the tape to feed 70 the same rearwardly.

In testimony whereof I have affixed my signature.

ABRAHAM BEBEL.
